TABLE LAMP

Roland C. Walker, 557 Franklin Ave., Brooklyn, N.Y.

Filed Aug. 9, 1965, Ser. No. 86,490

Term of patent 14 years

(Cl. D48—20)

Fig. 1.

Fig. 2.

Fig. 3.

FIG. 2 is a top plan view thereof,

FIG. 3 is a side elevational view thereof,

FIG. 4 is a side perspective view of a modified form of the design shown in FIGS. 1, 2 and 3, the modification consisting of the addition of a cover upon the top of the lamp shade thereof,

FIG. 5 is a top plan view thereof, and

FIG. 6 is a side elevational view thereof.

The dominant features of my design reside in the portions shown in full lines.

This application is a continuation-in-part of my co-pending application Serial No. D. 80,079, filed May 20, 1964.

I claim:

The ornamental design for a table lamp, substantially as shown and described.
